[57] **ABSTRACT**

Transportation units for goods are prepared by placing the goods between pressure distributing means in the form of end plates with lateral displacement resistance means, concentrated load or shear distributing resisting means, or shear resisting means positioned at suitable intervals along the length of the unit, and the unit is then made to act as a prestressed beam or prestressed structural unit by applying pressure to the pressure distributing means by the use of tendons maintained under tension in use.

METHODS AND MEANS FOR THE TRANSPORTATION OF GOODS

This invention relates to methods and means for the transportation of goods.

There is considerable interest today in what is known as "containerization." With present apparatus for containerization, however, the general aim is simply to provide a large fixed size packing case of permanent construction, which has transporting facilities associated therewith.

Such containers must be of at least sufficient strength to support their own weight, the weight of the goods and superimposed loadings, and transfer these loadings to supports or lifting points.

To keep the goods themselves within the confines of the container, the goods depend generally on being held together and on to the deck by gravity as well as requiring restraint from the sides of the container. In consequence, containers themselves tend to be bulky even in a "collapsed" condition. Space use, stowing and unloading are not always efficient and often additional means have to be provided to prevent undesirable load movement of goods inside the container. Very often a flexible load division is desirable, but although some containers can be coupled as modules or sections into a larger load, in practice economics preclude or severely limit the scope of this.

It is therefore an object of the present invention to provide methods and or means of the transportation of goods which will obviate or minimize the foregoing disadvantages in a simple yet effective manner, or which will at least provide the public with a useful alternative.

Accordingly, in one aspect, the invention may broadly be said to consist in a method of preparing goods, in the form of discrete articles or packages, for transportation, said method comprising the steps of assembling a plurality of discrete articles or packages between a pair of pressure distributing means to form a transporting unit, the discrete articles or packages being associated with lateral displacement resisting means adapted to resist displacement of the discrete articles or packages from their relative positions in planes parallel to the pressure distributing means and connecting the pressure distributing means to each other by a tendon or tendons and applying and maintaining tension by use of the tendon or tendons to pull the pressure distributing means towards each other so as to apply and distribute pressure over the goods so that the goods are precompressed by the pressure, so that the combination of apparatus and goods will behave and act as a prestressed beam or a prestressed structural unit with the substantial bulk of the goods remaining under compression, and with the tendons remaining under tension so as to remain structurally and dimensionally stable in normal use and at least within a normal range of levels and positions of the combination.

In a further aspect, the invention consists in transporting apparatus for discrete articles or packages of goods to form a transporting unit comprising a pair of pressure distributing means adapted to transmit pressure to goods placed between them, longitudinal tendons or a tendon adapted to apply tension to said pressure distributing means to cause said pressure to and over the goods placed between them and lateral displacement resisting means adapted to resist displacement on said discrete articles or packages from their relative positions in planes parallel to said pressure distributing means, the construction and arrangement being such that on said apparatus being loaded with goods to form a combination of apparatus and goods the goods are precompressed by said pressure so that the combination will act as a prestressed beam or prestressed structural unit with the goods remaining under compression and said tendons or tendon remaining under tension so as to remain structurally and dimensionally stable in normal use and at least within a normal range of levels and positions of the combination.

One preferred form of the invention will now be described with reference to the accompanying drawing in which

FIG. 1 is a side view of a transporting unit of apparatus according to the invention.

FIG. 2 is an end view of the unit shown in FIG. 1.

FIG. 3 is a collapsed view of the construction shown in FIGS. 1 and 2.

FIG. 4 is a plan view of four units according to FIGS. 1, 2 and 3, coupled as modules into a larger transporting unit.

FIG. 5 is a side elevation of a divisible unit.

FIG. 6 is a diagram of the tendon arrangement for the unit shown in FIG. 5.

FIGS. 7 and 8 are diagrams showing manners in which the unit in FIG. 5 may be divided.

FIGS. 9 to 11 show storage or loading systems.

FIG. 12 is a diagrammatic sketch of discrete articles incorporating displacement resistant means.

FIG. 13 shows alternative forms of such means.

FIG. 14 and 15 are diagrammatic views of lateral displacement resisting means or shear distributing means.

FIG. 16 is a diagrammatical side elevation of a transporting unit incorporating stirrup means.

FIG. 17 is a diagrammatic side elevation of a transporting unit for transporting free-flowing materials.

FIG. 18 is a perspective sketch of a corner hook means.

FIG. 19 is a diagrammatic perspective sketch of a further lateral displacement resisting means or shear distributing means.

FIGS. 20 to 30 are diagrams illustrating various combinations of pressure distributing means, lateral displacement resisting means and concentrated load or shear distributing means and tendon means.

FIG. 31 is a diagrammatic side view of a transporting unit including internal tendons.

FIG. 32 is a diagrammatic part cross section of a ship having mounted in it transporting units according to the invention.

FIG. 33 is a side elevation of a transporting unit using containers as pressure distributing means.

Referring to the drawings, apparatus for use in transporting goods in the form of discrete articles or packages is constructed as follows:

Pressure distributing means in the form of end members 1 are provided through which pressure may be applied to goods placed between such end members.

The end members may comprise frames having sheet material thereon, the sheet material being supported so as to remain in substantially the same plane when pressure is applied to the goods.

Thus the basic end members may each be constructed as a flat plate with or without reinforcing ribs or rims in a variety of materials (steel, aluminum, timber, fiberglass or the like). Its inside face may be flush, with or without indentable linings (e.g., rubber) of high friction or interference surface treatments.

Or alternatively it may have interference or locating ridges, locating protrusions or spigots, recesses, rims or a grid with wire mesh, tough fabrics or simply an open grid that locates on the load.

A pressure distributing means may also be simply a frame, grid or bands acting in a composite way with the first layer of articles or packages, arranged so that together they perform the function of applying the desired stress distribution onto the main payload.

The grid distributing the anchor reactions and the first layer of goods may be tied, stressed, coupled or the like to form in conjunction with the grid a rigid structural diaphragm or panel, e.g., flat tins or containers.

A stress plate may also consist of a composite construction, e.g., a metal frame, skeleton, grid with timber or the like decking with properties as above.

To facilitate stress distribution in applications where the end of the payload does not present a flush surface in a single plane, or does not conform to the surface of the end plate, packing blocks or adjustable pads may be superimposed on the stress plates inside surface to take up the voids and insure

conformity to the required stress distribution. Such a plate may have an adjusting arrangement on the frame to adjust local stress, like screwed plates, pads or the like. Such auxiliary components may become permanent fixtures to the stress plates surface. Where differences are minor, spring loaded or otherwise self-adjusting devices may be used. Alternatively, self-adjusting cushioning pads (rubber or the like) may be applied to the frames surface equalizing local pressures.

The pressure distributing means may furthermore consist of other arrangements insuring rigidity such as larger containers, boxes or bins themselves as seen in FIG. 33 in which two boxes or containers 70 are tied by draped tendons 71 held by tendon directing means 72 about a prestressed load 73 the containers 70 being cantilevered beyond supports 74.

The containers 70 may be merely boxes or in turn may be prestressed transport units according to the invention and one container 70 may be combined with an end member 1 if desired. Stress frames may be motorized or may be part of a truck or other rigid surface.

The pressure distributing means are always combined with lateral displacement resisting means and when used as supports or suspension points or with draping tendons, they combine with concentrated load or shear resisting means.

The frames may carry castor wheels 2 and screw jacks 3 having feet 4, or alternatively wheels may be provided as shown in FIG. 3 referenced 5. Means to prevent lateral displacement of the articles or packages in the lateral direction are provided in the form of a series of membranes or aprons 6 which may be suspended from a suspension cord or other flexible member 7.

The membranes or aprons may be flexible or rigid, provided with or without rims. Where a draped tendon arrangement 41 is adopted a solid shear apron 8 with tendon location fixtures may be used as a concentrated load and shear stress distributing means.

A continuous external tendon, parts of which are indicated in elevation at 9 and 10 is arranged around the unit and in the example, these are arranged to pull the end members 1 towards each other and to produce central stressing and then anchored or locked (with draped tendons system 41, the tendon also supplies an upward component of force which lifts the load directly).

The tendon may be tensioned by any suitable means, for example, by having the ends thereof threaded so as to pass through holes in the end members or brackets associated therewith or turn buckles may be provided or separate tensioning means may be used to draw the end members together, the tendons being then held either by a locking device, self-gripping or nonreturn device, or a clamp arrangement or by providing the end of the tendon with a length of chain which may be locked with locking plates behind the links. Holes 11 are provided in the cross member, through which pins 12 may be inserted, whereby further unit 13 may be fixed end on as shown dotted in FIG. 1. When empty the end frames 1 may be moved towards each other as shown in FIG. 3 with the tendon as shown in 9 and 10 folded and with the aprons 6 suspended adjacent to each other so that the empty unit takes up little space. The empty units may be further coupled to others to form packs to form transporting units themselves (as dotted FIG. 3).

In FIG. 4 four units 14 are shown coupled as modules end to end as well as side by side to form a larger single transporting unit, the modules so constructed and stressed to perform as a separate transporting unit or as part of a larger beam or unit.

The coupling fixtures may also be used however to simply link the units together for stable stacking arrangements.

Referring to FIG. 5 a divisible unit is shown comprising two portions 15, in the illustrated sample separated by double split boards 16. The tendons 17, FIG. 6 are provided with connecting links 18 which may be broken, and where split boards are used the hooks 19 engage with eyes on the appropriate split board 16 as shown in FIG. 6, the tendon system of a continuous external type is tensioned as a whole by the nut 20 being engaged on a screw spindle 21.

Such systems may after stress release be divided to form boxes comprising two mobile sections, by jack-knifing the released unit by means of a ram 22 between the split boards 16 as shown in FIG. 7, or by placing and releasing the unit on end 5 in the form box as shown at 23 in FIG. 8 and pivoting the upper portion on a fulcrum 24 as shown by the arrow 25.

FIG. 9 shows a suspension system in which the aprons or membranes 6 are suspended from flexible members 26, from a structure 27 or 28 and thus the specially adapted aprons or membranes 6 may be used as shelves for storage in the place of a storage rack, or the membranes or apron 6 may have the articles or packages placed thereon for loading before the end frames are tensioned.

15 Loading may be effected in several different ways and for example as shown in FIG. 10 empty units 28 may be fed along monorail 29 until a loading station is reached in which the unit is stretched out to its full length in a load former with expandable sides and bottom 30 and goods or articles may be fed through a feeding chute 31 to pass into the spaces 32 between aprons 6, each space 32 being filled before either the chute or the space is moved to fill the next empty space. Alternatively, spaces may be filled simultaneously. After this has occurred stressing at the end frames can take place and the monorail 20 then continues to storage rails and/or ultimately to a truck loading bay as shown in FIG. 11 where two coupled units or one unit consisting of two modules are suspended over a space beneath which a truck or trailer tray 23 may be arranged and the driver may release a stop mechanism 34 and after hooking a hook 35 to the front units and releasing the unit the truck or trailer may then move forward taking the unit with it. Because the monorail 36 slopes downward and may also have an extra drop section 37 the weight of the units is transferred to the truck tray which may then drive off without the driver having to leave his cab as even a despatch docket could be placed in a bracket 38 for extraction by the driver. The driver could also operate a hook 39 by remote control to engage and hold in position the rear end of the rear unit 40. Many other loading and unloading systems may of course be devised.

25 40 It will be appreciated that the general effect of the invention is to provide a prestressed beam or prestressed structural unit of goods or bulk material supported on at least two bases or suspended by at least one or two suspension points. Such a beam would have to resist or cope with the effects of general bending, shearing, concentrated loads or stresses as well as tendencies for lateral displacement of the goods or discrete or packages within a normal range of levels and positions of the unit.

45 50 Transportation units of discrete articles do not possess tensile properties as such but once precompressed to certain values compression can be reduced or varied, while a degree of compression aided or unaided provides slip or shear resistance between adjoining articles in the direction of compression.

55 60 In consequence, with lateral displacement resisting means provided, a prestressed beam or unit of discrete articles or packages can behave structurally in a substantially homogeneous manner and in conjunction with concentrated load and shear distributing means various constructions of transporting units can be devised.

65 Bending causes stress patterns in a particular cross section of a beam with a compressive component and a tensile component at opposing sides of the neutral axis of a unit, while shear stresses increase towards the supports. In devising a particular unit, the aim of the technique is to minimize, counteract or distribute the effects of bending and shear stresses, to create opposing stress patterns or at least maintain an adequate degree of compression in the substantial bulk of the goods to maintain shear resistance and general cohesion in the unit and to allow the unit to behave in a substantially homogeneous manner within the safe compression stress values and shear factors of the goods or bulk materials.

70 75 In an end supported beam for example, subjected to its own weight, a maximum bending moment is experienced in the middle of the span, producing maximum tensile action at the

bottom and maximum compressive stress at the top of the beam. If the resultant of prestressing forces is applied centrally to the neutral axis of the unit through the pressure distributing means, to a value neutralizing the tensile action encountered this could double the maximum compressive stress already in the unit (above the neutral axis). If this is undesirable, the prestress resultant could be applied eccentrically, e.g., below the neutral axis of the pressure distributing means and the unit, producing through the pressure distributing means a counter moment at the ends or an opposing stress pattern throughout the aggregate, requiring less total prestress and less maximum total compressive stress on the goods, while neutralizing tensile action.

However, if applied with eccentricity exceeding one sixth of the depth of the unit, assuming an oblong or square cross section, the constant prestressed pattern would itself develop a tensile tendency at the top, which would result in the center cross section, not only in the neutralizing of tensile tendencies or action at the bottom, but an actual reduction of the compressive bending stresses at the top.

At the end of the beam however, this pattern would fail to produce compression at the top end of the load, which generally would be undesirable and against the principle of avoiding absence of compression.

One manner in which the various difficulties may be met is for the tendons to be draped as shown in an exemplary manner by the tendons 41 shown in FIG. 1, utilizing tendon location means associated with a concentrated load or shear stress distribution means 42 at suitable intervals to give the desired drape to the tendons. Such draped tendon arrangements would tend to pull the load up in the center, counteracting the bending moments applied by selfweight, while also reducing shear stresses in the goods close to supports.

By this method, sag or deflection or dimensional stability generally can be controlled in the larger units or even reversed to an extent required, and the unit could be made to "hog up" if desired. By moving one or preferably both supports in from the end, with the aid of concentrated load or shear distributing means, the effects of the loadings and bending can be balanced and distributed and the maximum bending moment due to self weight or applied weight may be considerably reduced and with for example supports about 20 percent in from the ends, the bending moments over the supports and in the center are approximately equal, but acting in opposite directions and would be only about 15 percent of those in the simply supported cases. Assuming adequate shear resistance in the latter case, prestressing can now be reduced almost proportionately if central stressing is adopted, but with draping the tendons at the ends and in the middle both compression values and shear stresses can be reduced further still and deflections minimized, eliminated or reversed.

A prestressed beam or unit of discrete articles subject to conditions previously described may also consist of sections or modules which may be transporting units in their own right produced by the method, but may be mechanically coupled or stressed together as modules at their pressure distributing means to form a larger sectional structure or load as exemplified by FIG. 4. The modules and components are designed to withstand such loadings as will be met in separate use as well as in use as sections in the larger composite transporting unit. Any of the plurality or pressure distributing means of the modules in such a composite load or structure may be designed to act for example as concentrated load or shear distributing means (support or suspension means). Preferred methods would be whereby the modules are coupled end to end, side to side, coupled vertically or a combination of any or all of these.

In the case of units with supports in from the end several units may also be coupled or stressed however at the concentrated load or shear distributing means to form a larger transporting unit.

Shear resistance between compressed faces of discrete articles or packages and/or other surfaces may be increased

generally by means of increasing the friction co-efficient or interference factor between their areas or points of contact or providing more positive locating or keying means between them such as incorporating interlocking arrangements, rims or the like or the insertion of linking means between them such as spokes, pins, couplings, serrated materials, indentation wires or keying devices which can embed or key themselves in the compressed surfaces of the goods.

- In the case of certain bulk materials such as bulk wool continuous lateral stirrups associated with internal longitudinal tendons will assist shear resistance. Where discrete articles or packages in a transporting unit are discontinuous in lateral planes, preferred lateral displacement resisting means may consist of means creating or simulating lateral continuity of the goods over a cross section, preferably and substantially by the aid of compression in the unit. Preferred means may comprise discrete internal fixtures, tying or anchoring laterally adjacent goods together (e.g., tying and strapping or hooking) while such fixtures or goods may also or in addition be interconnected themselves by common means. Alternatively, shear resisting means previously referred to, depending substantially on compression for their effectiveness may be laterally connected or be substantially continuous over a lateral cross section such as flexible or rigid membranes, diaphragms or aprons 6 referred to with or without external rims or other continuous or semicontinuous inserted means. The latter arrangements connect both laterally and in the direction of compression.
- Laterally continuous goods or goods arranged to behave laterally continuous may themselves act as diaphragms, membranes or lateral displacement resisting means generally, to axially adjacent goods in the transporting unit.
- Later displacement resisting means such as membranes or the like may be incorporated as integral parts in the transporting apparatus (FIG. 1) or be separate parts.
- Alternatively, lateral continuity may be simulated by interlocking or overlapping of goods in some applications but with other constructions it is preferable to provide displacement resisting means which are associated with the individual articles or packages. Thus for example referring to FIGS. 12 and 13, discrete articles 43 such as boxes, bags or cartons are provided with flaps 44 and 45 which flaps may be repeated from other edges from the discrete article. The flaps 44 and 45 are shown overlying other discrete articles 46 and of course the pattern is repeated as desired, either with the flaps in horizontal plane as shown in FIG. 12 or in the vertical plane or in any plane or combination of planes as desired. The flaps 44 and 45 may for example be of hessian or other suitable material, but could also comprise flexible members, e.g., round members 47 or strips or other flexible members and may for example have enlarged portions 48 on the ends of single members 49 rather than the loops 47.
- In some constructions, lateral displacement resisting means can be provided by stirrups 50 and 51 (FIGS. 14 and 15) having either hooks, pins, protrusions, ridges or locating fixtures or membrane sheets in conjunction with the tendons. For example in high density bulk wool, lateral expansion can be resisted by lateral stirrups at intervals along the span and around an internal tendon arrangement or hooked thereto.
- Tendons may be arranged outside the load in conjunction with stirrups to restrain lateral displacement or expansion of the goods. For example as shown in FIG. 16 a unit of short logs or carcasses 52 would expand laterally under pressure in at least one plane unless the external tendons 53 arranged on the expanding sides of the units are restrained by stirrups 54 at intervals along the span having rings 55 through which the tendons 53 pass.
- Preferably such stirrups maintaining such restraining tension could be of a resilient nature maintaining a prestressing effect in lateral planes.
- In the case of free flowing materials or the like a construction shown in FIG. 17 may be used in which a sheath or tube 54 is divided at intervals by membranes 55 the membranes re-

sisting lateral displacement and the construction in effect comprising a series of separate packages 56 joined to each other at the edges. The parts of the sheath between membranes will be in tension, there being some bulging as shown. Tendons may be internal and/or external or draped as desired.

Further lateral displacement resisting means are illustrated in FIGS. 18 and 19. Thus in FIG. 18 hook means 57 may comprise a ring 58 if desired through which a tendon may be passed and a series of arms 60 having pins 61 which may extend into wool bales. A similar construction is shown in FIG. 19 in which a disc 62 has serrations 63 and cracked out portions 64, the cracked-out portions being engageable against faces of say cartons 65 and the serrations engaging such faces of cartons. The serrations could be replaced by pins engaging recesses in the cartons or boxes. To provide the serrations the edges could be castellated. Lateral expansion or buckling could also be resisted by wrapping spiral reinforcing around a unit.

Where the goods themselves cannot cope directly with concentrated loads or heavy shear concentration due to supports, suspension means, tendon drape or other superimposed loads, concentrated load or shear distributing means may comprise means or arrangements that spread the load or shear forces in the form of lateral compression into the load.

According to application, concentrated load and shear distributing means may be employed inside, or at the ends of the load comprising of means such as for example shear panels, sheets, grids or aprons 42 (FIG. 1), the latter used for example to distribute the concentrated load due to draping tendons in the tendon locating fixtures, which would be incorporated in such load and shear distributing means, into the form of shear into the unit in lateral planes.

Other preferred forms may consist of panels, sheets, grids, provided with shear transmitting means and reinforced according to the nature of the concentrated load, such means to cover part or whole of a unit's lateral cross section for shear coverage. Such means may be combined of course with lateral displacement resisting means and other means and whenever the pressure distributing means is used as a support or as a means of suspension, such means would also be combined with a concentrated load or shear distributing means.

Tension maintaining means or tendon systems may consist of a high strength rope or ropes, cable or cables, strand or strands, capable of maintaining substantially constant tension or adequate tension regardless of the behavior of the goods within the transporting unit.

Tendons would have required elastic properties or be associated with means simulating such properties such as springs or similar devices.

Continuous tendon runs round or through the load several times in conjunction with pulleys, etc. Individual tendons may run internal or external to the load.

The invention can be particularly effective in conjunction with goods which are also to be compacted or compressed generally to reduce volume in transportation, provided the pressures are moderate or the goods exhibit a marked hysteresis effect on release of compression, such as for example wool, where the initial compression to achieve high density wool is high but after relatively little relaxation and decreased density a very large decrease in compression results, adequate to maintain high density and within the range of normal prestressing requirements. The advantages of combining this process are considerable.

The invention envisages the combination of:

- a. Pressure distributing means
- b. Shear resisting means
- c. Lateral displacement resisting means
- d. Concentrated load or shear distributing means, and
- e. Tensioning means.

Thus in FIGS. 20 to 30 various combinations of these main means are illustrated. In each case, the reference letters to the main means are directed to the parts which provide the various features.

The shear resisting means have been referred to earlier.

A further mode of operation is to pass a tendon or tendons interiorly of the load, that is to say with some of the discrete articles or packages on the outside of at least some of the tendons thus as shown in FIG. 31 where a central tendon 65 is disposed between end plates 1 and of course alternative or additional tendons 65a could be provided.

This figure also shows transverse rails which could be solid as shown at 66 or of channel form as shown at 67 or other convenient shape.

These rails or channels would form a continuous rail or track when units are side coupled. This facilitates stacking of subsequent tiers particularly if the supports of the units have wheels or retractable wheels to match track. Alternatively a transporting dolly may be used in rails. It is a feature of the method that subsequent tiers of units or coupled units may cantilever over the preceding tiers, so that for example, full use can be made of non perpendicular sides in some shipping.

As shown in FIG. 32 where units 68 are shown mounted in a ship 69 and cantilevered out to use available space.

The invention provides the following advantages:

1. the ability to crate large loads at lower cost, lower tare weight, lower space loss, lower upkeep and cleaning cost per ton of unit load.
2. components after use occupy a very small amount of space, and are light, so that a plurality of such components may be coupled together to form large bulk loads by themselves, for return,
3. the load size of any one unit may be varied as required, by varying the length of the unit while components adjust to actual payload size,
4. units may be designed as modules of a larger load, the modules to be simply coupled or stressed by various means at the end frame, sideways, endways, or top or bottom, or combination of any of these, at any stage providing economical flexible systems of loading break down, load build up or changing of modular loads.

Such modular systems allow large loads for transportation, while at any stage provide a choice to a smaller but integrated load system without leaving bulky components behind after the load has been broken down. Such unit load system may be used, for example, where only smaller handling gear is available.

5. load cohesion by controlled prestressing has two main features:
  - a. it gives virtually homogeneous units of greater structural stability with a minimum of relative movement within the load,
  - b. it is independent of gravity, gravity decks or within wide margins, the position of the unit relative to the direction of gravity depending on the application.

These give secondary features:

- i. The prestressed units, much like solid blocks or containers in this respect, need a minimum of load binding means to support and enable more stable stacking arrangements generally.
- ii. Due to absence of rubbing or sliding of the load units or bulk materials within the total unit, there is less damage and less kinetic energy losses or heat generation within the units,
- iii. To the extent that the total surface area of the goods exposed to atmosphere is reduced in the prestressed aggregate, the heat exchange rate of the unit is affected accordingly, resulting for example in the reduction or elimination of insulation or refrigeration requirements of refrigerated goods during various stages of transportation,
- iv. Contrary to the major conventional systems which depend on cohesion by gravity, prestressed units do not suffer from the same limitations when handled or used on slopes or in positions deviating considerably from the horizontal level, (or even in all positions for a large number of applications) and be exposed to considerable acceleration forces without the load cohesion or structural stability of the units being significantly af-

- fected. This considerably increases the possibility and scope of handling means generally for internal and external transportation, and specifically increases the possibilities of economic use of gravity for the moving or feeding of units along slopes or rails, e.g., monorails.
- v. The units in a substantially horizontal position without (gravity) decks or other major obstructions on the top or bottom of the unit can make the maximum economic use of gravity in both charging or discharging a unit.

This may, for example, be done in the case of charging a unit in a variety of positions with the aid of a "load former" or constructions which conform to the general shape of the load in part or whole during the load forming operation, with the load units or the bulk material fed in from the open top or sides by chutes hoppers or other means, by semi or fully automated means according to the application. Discharging may be performed either in one stacked block or assembled arrangement from the bottom of the unit, or into a special hopper, or the unit is moved into a discharging former consisting of two sides and a bottom. The latter former is constructed so that a determined portion is open when required. Thus, the load units or bulk units after stress, released in the discharge former, may be discharged in loads or section with or without controlled output.

vi. The features in (iv) and (v) above, alone or in combination, allow many internal handling systems to be put into effect particularly systems based on sloping rails as above described, mostly gravity fed, and semi or fully continuous from inward goods to despatch which can be fully integrated with the actual production process, or may be semi or fully automated.

I claim:

1. A method of preparing goods in the form of discrete articles or packages with plane or substantially plane end faces for transportation comprising assembling said articles or packages into a unit, placing pressure distributing means in a vertical plane at each end of said unit, prestressing said pressure distributing means against each other about the discrete articles or packages by means of tendons, introducing lateral displacement resisting means between said articles or packages, thereby prestressing said tendons to such a degree that the

unit acts as a prestressed beam, and disposing shear resisting means at intervals along the length of the load parallel to the plane of application of pressure by said pressure distributing means.

- 5 2. A method as claimed in claim 1 further comprising increasing the frictional coefficient factor between areas of contact of said goods to thereby dispose said shear resisting means.

- 10 3. A method as claimed in claim 1 further comprising positively locking the goods one to another by locking means selected from interlocking arrangements, rims, and linking means inserted between the goods to thereby dispose said shear resisting means.

- 15 4. A method of preparing free-flowing materials for transport comprising the steps of placing the free-flowing materials in a series of compartments, each compartment having a common wall with the next compartment, each compartment when filled being closed, applying pressure distributing means to the series of compartments, connecting said pressure distributing means to each other by tendon means and applying and maintaining tension by use of the tendon means to pull the pressure distributing means towards each other so as to apply and distribute pressure over the goods whereby the goods are precompressed by the pressure causing the combination of apparatus and goods to behave and act as a prestressed structural unit such as a prestressed beam with the substantial bulk of the goods remaining under compression, and with the tendons remaining under tension so as to remain structurally and dimensionally stable in normal use and at least within a normal range of levels and positions of the combination.

- 20 5. A method of preparing goods in the form of discrete articles or packages with plane or substantially plane end faces for transportation comprising assembling said articles or packages into a unit, placing pressure distributing means in a vertical plane at each end of said unit, prestressing said pressure distributing means against each other about the discrete articles or packages by means of tendons, introducing lateral displacement resisting means between said articles or packages, thereby prestressing said tendons to such a degree that the 30 unit acts as a prestressed beam, and suitably disposing concentrated load shear distributing means to distribute concentrated load shear stresses.
